MACHINE FOR FLESHING AND/OR
SCRAPING HIDES

Luis Alberti, Buenos Aires, Argentina

Application June 10, 1948, Serial No. 32,087
In Argentina March 22, 1948

4 Claims. (Cl. 69—20)

1

The invention relates to a new type of machine destined for fleshing and/or scraping hides generally which offers many advantages in comparison with machines which are now in use for the same purpose.

Machines which presently are used for fleshing or scraping hides are stationary and each one performs only one operation, as their construction does not enable changing the mechanisms for performing both operations, that of fleshing and that of scraping with the same machine. On the other hand present machines for fleshing hides perform the operation by gaging uniformly the thickness of the hide which is not in accordance with the principles of rationality, as fleshing a hide at a determined thickness means wasting a percentage thereof.

It must be understood that the hide, principally that of cattle, when fleshed carefully by hand with a knife, will show a great variation in thickness; it is then easy to suppose what will happen when fleshing is done with a stable machine. Many surfaces without flesh are cut away uselessly due to uniformity of cutting. Considering these disadvantages, the present movable machine has been conceived which, as it adapts itself partially to relatively small surfaces, can flesh different hides with a minimum percentage of waste. On the other hand the substantial difference between both mechanisms of which the first one is very heavy, complicated and expensive, whereas the second one is light, easy and economical, does not give occasion to doubt about its adoption as a highly practical machine. By replacing only the fleshing cylinder by a scraping cylinder, a second working operation will be performed which present machines cannot do.

On the other hand an ingenious fastening device will contribute so that the handling of said machine does not cause weariness to the worker, as its disposition is devised in such a way that the machine may be used during lengthy and continuous periods.

For the purpose of explaining quite clearly the nature of the invention and the manner in which it can be carried into practice, an example thereof will be described hereafter with the help of the accompanying drawings.

Figure 1 shows the new machines provided with a fleshing cylinder, seen laterally.

Figure 2 shows the same machine seen in front.

Figure 3 shows a partial view of a scraping cylinder, which element placed into the same machine and instead of the fleshing cylinder will perform another manufacturing process.

2

Figure 4 shows the device which fastens the machine, seen laterally.

Figure 5 shows a part of the fastening device, seen in front.

5 Figures 6, 7 and 8 show different positions of the fastening device and the machine.

Body 1 of the machine will be provided with a U-shaped fork 2 the extremes of which will be inserted into pins 3 fixed to the body so that a 10 rocking movement may be given to the machine. Body 1 carries the fleshing or scraping cylinder 4 (see Figure 3); in both cases shaft 5 seated in bearings 6 will be duly attached to the assembly.

15 An electric motor 7 which is situated at the posterior and inner part of body 1 will transmit the necessary rotation to cylinder 4 by means of pulleys 8 and 9 and belt 10.

On the other hand at the extremes of shaft 5 20 there will be provided pillows 11 having a well arranged surface so that, by means thereof, the worker in charge of the machine may guide it with both hands over the surface of the hide to be treated.

25 At the center of fork 2 which corresponds to the back thereof an element will be provided which has the value of a hinge; one of the blades thereof, viz. that indicated by reference 12, will be attached laterally to fork 2 by means of screws or rivets 13; the opposite blade 14 which is free will have a perforation 15. On the other hand axle 16 of the hinge which extends outside thereof will carry an element 17 which is provided with two cams 18 and 19 and which besides will have an arm 20 curved more or less in an angle of 90°, the extreme of which will end at a ball 21 of determined diameter and weight.

Hinge blade 14 as well as element 17 will have an independent movement, but both will turn round axle 16 of the hinge. As to cams 18 and 19 it may be mentioned that both are substantially equidistant from axle 16, and as one of them, viz. that indicated by reference 18, will exceed extreme 22 of hinge blade 14 when element 17 is turned about the axle, as a result thereof said cam 18 will touch against plane 23 of said hinge blade 14; whereas, when said element 17 is turned in an opposite sense, opposed cam 19 will touch plane 24 of hinge blade 14.

40 45 At the front part which corresponds to the superior plane of body 1 of the machine, and coinciding in direction with the center of the hinge, there will be put a forked pole 25 which is fixed to body 1. In the axle 26 thereof a 50 lever 27 will be maintained, the body of which

will pass through perforation 15 of hinge blade 14. Perforation 15 will be lengthened so as to enable lever 27 to reach a pronouncedly oblique position as compared with its normal position.

At axle 26 of forked pole 25 a spring 28 will be put so that the tension of this latter one obliges lever 27 to stay always upwards.

At lever 27 and near the end thereof which is adhered to forked pole 25 a series of incisions 29 will be effected, which, when adequately cut, will enable lodging there in part of extreme 30 of hinge blade 14.

Operation is as follows: Figure 1 shows the pending machine in working position, viz. cylinder 4 is placed upon work plane 31. Parting therefrom and supposing that the person in charge of the machine wishes to have it out of contact with work plane 31, counterweight 21 must be in the shown position, which means to say that the action of counterweight 21, due to 20 gravity, will cause the cam 19 to touch the inferior plane 24 of hinge blade 14. When taking collateral handles 11 and lifting machine 4 which will turn upon pins 3, hinge blade 14 will slide along lever 27 and will drop into one of incisions 25 29 of said lever 27. In this fashion the height of the machine will be perfectly assured and it will be suspended at cable 32, as may be seen from Figure 6.

When the worker wishes to put the machine upon work plane 31, he will have to turn forwards element 17 which carries counterweight 21. In this case cam 18 will touch plane 23 of hinge blade 14 (see Figure 7), whereby, lifting the machine a little and turning always upon pins 3, hinge blade 14 may be withdrawn from any one of incisions 29, as may be seen in Figure 8. In these conditions the machine can be put freely upon work plane 31. For machines of a certain size and weight a series of orifices 33 30 amply distanced between one another may be provided, wherein fastening pins 3 to fork 2 can be put for the only purpose that the elevation plane of the machine results comfortable for the worker. As cable 32 may be provided with rotary unions or simply with knotted extremes action of the machine can be effected in all angles and planes which are desired.

When the machine is suspended as shown in Figure 1 and part of a hide to be fleshed or scraped is put upon the work table, whereas the rest of the hide is held in place, secured by the abdomen of the worker at the edge of the table or by any other adequate mechanical fastening means, treatment thereof will be begun, revolving rapidly the cylinder upon the surface it rests upon and displacing the machine slowly thereupon in different directions whereby in each case the desired effect will be had.

I claim:

1. A portable machine for the fleshing and scraping of hides, which comprises: A working cylinder pivoted for rotation in a supporting frame at the front end of said machine; a U-shaped rocking fork pivoted at one end thereof to said supporting frame, and suspended at the other end from an elevated position by means of a relatively flexible suspension means; a hinge pivotally supported from said U-shaped rocking fork by a pivot pin, said pivot pin being positioned at approximately the center of said hinge, said hinge having a blade which extends freely toward said supporting frame and working cylinder, and said blade being provided with an elongated aperture positioned therein; an element including an arm doubled approximately at an angle of 90 degrees, said element being pivoted at said pivot pin at which said hinge is pivoted, but at a point exterior of said hinge; a pair of cams supported on said element including said doubled arm, one of said cams being positioned on either side of said pivot pin and at an equal distance therefrom; a pole disposed at the front of said machine on the upper surface of said supporting frame, said pole being provided at its end remote from said supporting frame with a supporting fork; and a lever of substantially rectangular cross-section seated at one of its ends in said supporting fork, said lever then extending through said elongated aperture in said blade, said lever being provided with a series of incisions in its lower edge portion adjacent the end thereof supported from said pole by means of said supporting fork, said incisions being adapted to seat and retain said blade of said hinge which extends toward said supporting frame and said working cylinder.

2. A portable machine for the fleshing and scraping of hides as defined in claim 1, wherein one of said cams supported on said element including said doubled arm extends therefrom at a point beyond a point to which said blade of said hinge extends.

3. A portable machine for the fleshing and scraping of hides as defined in claim 1, wherein said element including an arm doubled approximately at an angle of 90 degrees is provided at one end thereof with a counterweight.

4. A portable machine for the fleshing and scraping of hides as defined in claim 1, wherein spring means are provided adjacent said supporting fork of said pole, said spring means normally urging said lever upwardly and away from said supporting frame and working cylinder of said machine.

LUIS ALBERTI.
